UNITED STATES PATENT OFFICE.

WILLIAM F. MILLER, OF NEWTON, MASSACHUSETTS.

INTERNAL-COMBUSTION ENGINE.

1,050,779.

Specification of Letters Patent. Patented Jan. 14, 1913.

Application filed July 19, 1905. Serial No. 270,357.

To all whom it may concern:

Be it known that I, WILLIAM F. MILLER, a citizen of the United States, residing at Newton, county of Middlesex, and State of 5 Massachusetts, have invented an Improvement in Internal-Combustion Engines, of which the following description, in connection with the accompanying drawing, is a specification, like letters on the drawings 10 representing like parts.

This invention relates to an internal combustion engine, and it has for its object to provide an engine of this type in which crude oils, such as crude petroleum, can be 15 successfully used as a fuel.

The main difficulty which has been experienced in prior attempts to use crude petroleum as a fuel in internal combustion engines is that the combustion of the crude 20 petroleum generates a residue which soon clogs the interior parts of the engine to such an extent as to render effective operation impossible. In my present invention I have provided a novel construction by means of 25 which this disadvantage is entirely eliminated, and an engine embodying my invention can be operated continuously for an indefinite period of time without any danger of the sparking device or other operative 30 parts of the engine becoming clogged by a coking operation.

Another difficulty which has been experienced in prior attempts to use crude petroleum is that the valves of the engine are 35 continually getting clogged. I avoid this difficulty in my present invention by eliminating all valves and substituting therefor a forcing mechanism which is adapted to force charges of oil under pressure in the 40 form of a spray into the cylinder at proper times.

My improved engine comprises means to deliver to the cylinder at predetermined times oil under pressure and in the form of 45 a spray, and other means to deliver an appropriate amount of compressed air to the cylinder. The compressed air and oil are delivered into the cylinder when the piston is at the end of its power stroke, and during 50 the backward stroke of said piston, the commingled air and sprayed oil is highly compressed, and at the appropriate time is fired by a suitable sparking plug. The means I employ for delivering the charges 55 of oil into the cylinder is so constructed that it is impossible for it to become clogged by

any impurities or foreign matter in the crude petroleum, and the manner of introducing and firing the charge is such that no coking of the parts results.

In the drawings, Figure 1 is a side view of my improved engine with parts broken out to better show the interior construction; Fig. 2 is a section on the line *x-x*, Fig. 1; Fig. 3 is a detail of the crank-shaft; Fig. 4 is a view of the spray device; Fig. 5 is a vertical sectional view of the pump for forcing separate charges of oil into the cylinder; Fig. 6 is a section on the line *y-y*, Fig. 5; Fig. 7 is a view of the cylinder of 70 the pump; Fig. 8 is a view of the piston thereof; Fig. 9 is a section through the pump cylinder and plunger on the lines *a-a* in Figs. 7 and 8; Fig. 10 is a similar view on the lines *b-b*, Figs. 7 and 8; Fig. 11 is a 75 detail of a starting or coaxing device, and Fig. 12 is a detail view showing the spraying end of the spray device.

3 designates the cylinder of the engine which may be of any suitable or usual construction, and 4 the piston which operates within the cylinder. Said piston is connected by means of a suitable piston-rod to a crank-shaft 5, the crank 6 of which operates in a crank-case 7. As stated above, my 80 improved engine is so arranged that air is forced into the cylinder at approximately the same time that the charge of oil is delivered thereto. One convenient way of thus delivering the air to the cylinder at the 85 proper time is to make use of the piston 4 as the air pump and also as the valve for opening and closing the air-supply port, and in the drawings, I have shown the piston arranged to operate in this way. For this 90 purpose, the lower end of the cylinder opens into and communicates with the interior of the crank-case 7, and the ends of the crank-case are closed by suitable heads 8 through 95 which the crank-shaft 5 projects. The closed crank-case also communicates with the interior of the cylinder through an air-duct or passage 9 which terminates in an air-port 10 so situated that it is uncovered by the piston when the latter reaches the 100 end of its power stroke. Air may be supplied to the interior of the crank-case 7 in any suitable way, although I have found the arrangement shown in Fig. 1 to have good 105 results. According to this arrangement, air is admitted to the crank-case through both 110 an inlet-port 11 which is controlled by a

suitable check-valve 12, and through a bypass port 13 which opens through the side of the cylinder into the interior thereof. During the upward stroke of the piston air is drawn into the crank-case through the port 11, and when the piston has nearly reached the upper end of its stroke, it uncovers the port 13 thereby permitting an added quantity of air to enter the crank-case 10 through said port. At the beginning of the downward stroke of the piston it covers and closes the port 13, and the further downward stroke compresses the air within the crank-case, the check-valve 12 preventing the air from escaping through the port 11. When the cylinder has reached approximately the end of its downward or power stroke, the piston uncovers the supply-port 10, and the compressed air within the crank-case 15 is admitted to the cylinder above the piston through said port.

As stated above, the crude oil is delivered under pressure to the cylinder in small measured charges, this delivery of the oil occurring substantially simultaneously with the forcing of air into the cylinder. The oil is delivered into the cylinder through a spray device 14 which is formed with a spray-nozzle 15. I have secured best results by using a spray-nozzle of the shape shown in Figs. 4 and 12 that is, one in which the eduction aperture is in the form of a narrow slit. This nozzle is connected by a suitable pipe 16, partly broken away in Fig. 30, to a forcing or feeding mechanism 17 which feeds into the cylinder the separate charges of oil. The feeding mechanism I have herein shown is in the form of a pump, and it comprises a pump-cylinder 18, shown 35 detached in Fig. 7, and a piston or plunger 19 operating within said pump-cylinder, said piston or plunger being shown detached in Fig. 8.

The pump-cylinder has an inlet-port 20 40 therein and an outlet-port 21, the inlet-port communicating with a suitable inlet-pipe 22, and the outlet-port with an outlet-nipple 23 to which the pipe 16 is connected. The piston or plunger I have herein shown is hollow for part of its length and is open at its upper or inner end. It also has an inlet-port 24 and an outlet-port 25 which are adapted to register at proper times in the reciprocation of the plunger with the inlet and outlet-ports of the pump-cylinder. The upper end of the pump-cylinder 18 is closed, and the pump-piston 19 is reciprocated by suitable mechanism hereinafter described.

When the piston is in the position shown 45 in Fig. 5, its inlet-port 24 registers with the inlet-port of the cylinder and oil is admitted to the interior of the piston.

There is preferably a small quantity of air 50 confined in the upper end of the pump-cylinder 18, and as the piston moves upwardly

after having received its charge of oil, thereby closing the inlet-port 24, this air is compressed and the oil is subjected to pressure. As soon as the outlet-port 25 of the pump-piston registers with the outlet-port 21 of the pump-cylinder, the charge of oil which is thus subjected to considerable pressure is forced out into the pipe 16 and from thence through the spray device into the cylinder by the expansive action of the compressed air in the pump-cylinder.

One convenient way of mounting the pump-cylinder is herein illustrated, although my invention is not confined to this construction. As herein shown, the cylinder 18 is confined within a suitable casing 26 which in turn is secured to the engine-cylinder in any suitable way, said casing having ports therein which communicate with the inlet and outlet-ports of the pump-cylinder and to which the pipes 22 and 16 are connected. The end of the casing is closed by a suitable head 27 which forms the end of the pump-cylinder. The pump-cylinder is shown as extending through a suitable stuffing-box 28 which prevents any leakage of oil.

The pump-piston may be operated in any suitable way. The engine herein shown is a two-cycle engine, and the piston, therefore, reciprocates synchronously with the rotation of the crank-shaft. In this type of engine I prefer to operate the pump-piston directly from the crank-shaft, and for this purpose have connected the lower end of the pump-piston to the eccentric-rod 29 of an eccentric-strap 30 which surrounds a cam or eccentric 31 on the crank-shaft.

My invention also involves means whereby the quantity of oil or the size of each charge of oil can be varied according to the demands made upon the engine. I accomplish this regulation of the size of the charge in the present embodiment of my invention by making the pump-piston capable of rotation in the pump-cylinder, thereby to vary the size of the inlet and outlet-ports. When the pump piston has the position relative to the pump-cylinder shown in Figs. 9 and 10, the inlet and outlet-ports are fully open and the maximum charge of oil is delivered. If said pump-piston were rotated within the cylinder, the inlet and outlet-port of said piston would be correspondingly reduced, and as a consequence a smaller charge of oil would be admitted at each stroke of the engine. Any appropriate mechanism may be employed for thus turning the pump-piston. That herein shown comprises a handle 32 which is mounted on the casing 26 to turn thereabout and which is connected by a pin 33 with an arm 34 fast to the pump-piston 19. By swinging the handle 32 about the casing the plunger may be turned into the desired position.

In the operation of the engine, the down-

ward or power stroke of the piston compresses the air in the crank-case and when the piston has reached the end of its stroke, it uncovers the air-supply port 10 and compressed air is admitted to the cylinder above the piston. At the same time, the piston uncovers the exhaust-port 35 and the burnt gases are exhausted, their exhaust being facilitated by the charge of air entering through the port 10. Just after exhaust has occurred and just after the air-supply port 10 has been completely opened and sufficient air has been admitted through the air-supply port 10 to scavenge the cylinder the outlet-ports in the pump-piston and pump-cylinder are brought into communication and the charge of oil is delivered into the engine cylinder through the spray device 14. The spray of oil is thus delivered into the incoming current of compressed air and thus becomes thoroughly commingled with the air. Upon the return stroke of the piston, the commingled charge of air and atomized oil is highly compressed, and at the proper time it is fired by a suitable sparking plug 36. During the upward movement of the piston, air is drawn into the crank-case through the port 11, and when the piston reaches the extreme upper limit of its stroke, the port 13 is uncovered and air is admitted therethrough.

I have found that by delivering the oil into the cylinder under pressure and in the form of a spray at the same time that air is forced into the cylinder, and then compressing the commingled air and oil to a high degree before firing it, that complete combustion takes place, and there is no danger of the parts becoming clogged by the coking operation.

In order to obtain the highest efficiency from my improved engine, it is desirable to regulate the amount of air delivered to the cylinder so that it will have the proper proportion to the charge of oil. When small charges of oil are being injected into the cylinder, a smaller quantity of air is necessary than when larger charges of oil are being used.

For regulating the amount of air delivered at each stroke, I have shown a regulating valve 37 which controls the duct 9 and by which the duct may be closed more or less according to the amount of air which it is desired to use at each charge.

I prefer to place suitable packing-rings 38 around the crank-shaft where it passes through the heads 8 so as to make an air-tight joint at this point.

In Fig. 10 I have illustrated a starting or "coaxing" device which may be employed if desired to assist in starting the engine. This comprises merely an oil-cup 38 adapted to contain gasoline or some other volatile oil which is connected to the air

duct 9 by means of a suitable pipe 40. 41 designates a suitable valve which controls the supply of oil from the oil-cup to the pipe 40. In starting the engine the valve 41 may be opened to admit a small quantity 70 of volatile oil to the pipe 40 and duct 9, and then when the crank-shaft is started by hand, the piston operates to force this oil commingled with air around into the cylinder where it is exploded. 75

I find that better results are secured when a certain volume of the burnt gases is retained in the cylinder after exhaust to be commingled with the fresh charge of commingled oil and air, the presence of the 80 proper amount of burnt gases assisting greatly in keeping the interior parts of the engine free from a deposit of coke and other residues. To thus secure the retention of the certain amount of burnt gas in the 85 cylinder, I make the upper or inner end of the piston with a chamber or recess 42 in which the proper amount of burnt gases is retained at the time of the exhaust.

I have shown the piston as scarfed or cut 90 away at 43 at a point opposite the air inlet port 10. The wall of this notch 43 constitutes a deflector to direct the incoming charge of oil and gas upwardly to the upper part of the cylinder. 95

It will be noted that my improved engine contains no regular inlet-valves which are liable to be clogged by the crude petroleum, the pump herein shown taking the place entirely of said valves. The pump 100 is of such construction that it will not be clogged by any crude oils that may be used as fuel.

The particular kind of pump herein shown is not essential to my invention although it 105 is the type of pump which I prefer to use.

While the drawings show the preferred embodiment of my invention it will be obvious that various changes may be made in the construction of the device without departing from the spirit of the invention expressed in the claims.

Having fully described my invention, what I claim as new and desire to secure by Letters Patent is:—

1. In an internal combustion engine, a cylinder, a piston therein, said cylinder having an inlet port situated to be opened by the piston when the latter reaches the end of its power stroke, a spray device having 120 an elongated mouth situated within said port and adapted to deliver oil directly into the cylinder, means to force a charge of oil through said spray device each time the port is opened, and other means to force 125 a charge of air through said port simultaneously with the admission of the oil to the cylinder.

2. In an internal combustion engine, a cylinder, a pump to force separate charges 130

- of oil into the cylinder, said pump comprising a pump cylinder having an inlet and an outlet port, and a hollow pump piston also having an inlet and an outlet port, and means to operate the pump piston to cause the ports thereof to register, at proper times with the ports of the pump cylinder.
3. In an internal combustion engine, a cylinder, and means to deliver oil thereto, said means comprising a pump cylinder having an inlet and an outlet port, and a hollow open-ended pump piston operable in said cylinder, said piston also having an inlet and an outlet port, and means to operate the piston.
4. In an internal combustion engine, a cylinder, and means to feed oil thereto, said means comprising a pump cylinder having an inlet and an outlet port, one end of said cylinder constituting an air chamber, and a hollow open-ended pump piston operating in said pump cylinder, said piston also having an inlet and an outlet port, and means to reciprocate the piston.
5. In an internal combustion engine, a cylinder, a pump to force charges of oil into the cylinder, said pump comprising a pump cylinder having an inlet and an outlet port, and a hollow pump piston also having an inlet and an outlet port, and means to vary the size of the ports, thereby to vary the quantity of oil in each charge.
6. In an internal combustion engine, a cylinder, a pump to force charges of oil into the cylinder, said pump comprising a pump cylinder having an inlet and outlet port, and a hollow pump piston also having an inlet and outlet port, and means to turn the pump piston relative to the cylinder, thereby to vary the size of the ports.
7. In an internal combustion engine, a cylinder, means to force into the cylinder at each stroke of its piston a quantity of air, means to inject into the cylinder at the same time a charge of oil under pressure and in the form of a spray and independent means to regulate the amount of air and oil delivered at each stroke.
8. In an internal combustion engine, a cylinder having an air supply port connected with a source of air supply, means to force air through said port at predetermined times, a spray device directed toward the current of air as it enters the cylinder through said port, means to force oil into the cylinder through said spray device and independent means to regulate the amount of air and oil delivered at each stroke.
9. In an internal combustion engine, a cylinder, a piston therein, said cylinder having an inlet port situated to be opened and closed by the piston when the latter approaches and recedes from the end of its power stroke, means separate from the piston to place under considerable pressure a fixed charge of oil at each stroke of the engine and to hold said charge under compression until a period of time subsequent to that at which the inlet port is completely opened and then to deliver said charge directly into the cylinder through said port.
10. In an internal combustion engine, a cylinder, a piston therein, said cylinder having a single inlet port situated to be opened and closed by the piston as the latter approaches and recedes from the end of its power stroke, means to deliver directly into the cylinder through said port fixed charges of oil in the form of a spray, an air passage communicating with said port, means to deliver air under pressure through said passage simultaneously with the delivery of oil, means to regulate the amount of oil delivered, and a valve in said passage to control the amount of air delivered.
11. In an internal combustion engine, a cylinder, a piston therein, said piston having an inlet port situated to be opened and closed by the piston, a flat spray device located within said port, means to force air into the cylinder through said port, and means to deliver oil through said flat spray device subsequent to the opening of said port whereby the air has time to scavenge the cylinder before the oil is admitted.
12. In an internal combustion engine, a cylinder, a piston therein, said cylinder having an inlet port situated to be opened and closed by the piston when the latter approaches and recedes from the end of its power stroke, means for forcing air under pressure into the cylinder through the inlet port when the latter is open, a fuel-feeding pump having inlet and outlet ports, means to open and close said ports, means connecting the outlet port of the pump to the inlet port of the cylinder, and means to operate the pump in timed relation to said piston thereby to place a charge of oil under compression in the pump during each stroke of the engine and to open the outlet port of the pump subsequent to the opening of the inlet port of the cylinder and the initial delivery of air therethrough whereby the cylinder will be scavenged by the entering air before the oil is delivered.
13. In an internal combustion engine, a cylinder having an inlet port, a piston in the cylinder operating to open and close said inlet port, a pump having a compression chamber, means to put a fixed quantity of oil under pressure in said compression chamber during the power stroke of the piston, and means other than said piston to open communication between said compression chamber and the cylinder at a period of time subsequent to the opening of said inlet port whereby oil will be delivered to the cylinder under pressure.
14. In an internal combustion engine, a

cylinder having an inlet port, a piston in the cylinder operating to open and close said port, means whereby air is forced into the cylinder through said inlet port when 5 the latter is open, a fuel-supply pump provided with an outlet port, means connecting said outlet port with the inlet port of the cylinder, and means to operate said pump to place fixed charges of oil under compression therein during the power stroke of the piston and to open the outlet port of the pump after the inlet port to the cylinder is open whereby the delivery of oil is delayed until the cylinder is scavenged.

15 15. In an internal combustion engine, the combination with a cylinder having a piston therein and a crank shaft, of a pump provided with a piston for feeding oil directly

to said cylinder, said pump having inlet and outlet ports which are opened and closed 20 by the movement of the pump piston, and means to vary the size of the inlet port.

16. In an internal combustion engine, the combination with a cylinder having a piston therein and a crank shaft, of a pump for feeding oil directly to said cylinder, said pump having inlet and outlet ports, and means to vary the size of the inlet and outlet ports simultaneously.

In testimony whereof, I have signed my 30 name to this specification, in the presence of two subscribing witnesses.

WILLIAM F. MILLER.
